ELECTROLYTIC APPARATUS

Joseph C. Schumacher, Los Angeles, Calif., assignor to Western Electrochemical Company, Los Angeles, Calif., a corporation of Nevada

Application October 31, 1945, Serial No. 625,859

3 Claims. (Cl. 204—278)

1

This invention relates to an improved electrolytic cell and in particular to an electrochemical cell for use in making perchlorates.

One object of the invention is to provide an electrolytic cell of the non-diaphragm type for the electrolysis of aqueous solutions. Another object is to provide an improved electrolytic cell in which the operating conditions for an electrochemical reaction may be adequately controlled. Still another object is to provide an anode structure for an electrolytic cell utilizing thin sheets of platinum metal. These and other objects are attained by my invention which will be understood from the following description, reference being made to the accompanying drawings in which:

Fig. 1 is a top elevational view of a preferred form of my electrolytic cell;

Fig. 2 is a side elevational view of the same with parts broken away to show the interior arrangement;

Fig. 3 is an end elevational view of the same;

Fig. 4 is a cross-sectional view taken on the line 4—4 of Fig. 2;

Fig. 5 is a cross-sectional view taken on the line 5—5 of Fig. 2; and

Fig. 6 is a cross-sectional view taken on the line 6—6 of Fig. 2.

My improved electrolytic cell is particularly adapted for use in the electrochemical oxidation of sodium chloride to sodium perchlorate in aqueous solution and the following description will be made with particular reference to a preferred form for use in carrying out this reaction, although it will be understood that the invention may be employed in other electrochemical reactions involving other chemical transformations.

In general my electrolytic cell consists of an elongated trough-like steel tank having an electrically insulating cover through which extend thin platinum sheet electrodes supported by suitable holding members, with cooling coils disposed between electrodes, and cooling jackets provided on the outer side walls of the tank, the steel tank and attached steel parts inside the cell constituting the cathode.

Referring to the drawings, my electrolytic cell consists of an elongated steel tank 11 with an open top and outwardly extending flanges 12 around the upper edge. Channels for cooling liquid are provided by longitudinally placed steel jackets 13, welded to the two side walls 11A of the tank 11, these being subdivided by horizontal partitions 14 to distribute the circulating

cooling liquid. Further control of the temperature in the cell is attained by the use of a tier of steel tubes 15 extending centrally through the electrolyte compartment of the cell between the anodes 17, the ends of these tubes being connected to manifolds 16 on the two ends of the tank 11 so that the cooling liquid may be circulated not only through the side wall jackets 13 but also through these tubes disposed between the platinum cathodes 17 within the electrolyte compartment of the cell. The cooling water enters through the pipe 21 and is withdrawn through the pipe 22. The cell cover plates 18 consist of sheets of chemically resistant artificial stone material, for example, sheets made of compressed mixtures of Portland cement and asbestos, which sheets are attached by bolting to the flange 12 around the upper edge of the tank. Slit openings 19 fitting the platinum electrode sheets 20 are provided in this artificial stone cover 18 for the insertion of the anodes. The steel surfaces of the tank 11 and the water-cooling tubes 15 in contact with the electrolyte serve as the cathode for the cell.

25 The electrolyte is introduced through the influent pipe 21A and is withdrawn through the overflow or effluent pipe 22A tube. The cell is especially adapted for use in a process requiring the circulation or recirculation of the electrolyte in and out of the cell but it may also be used in a discontinuous process or in a batch or intermittent process in which the cell is filled with electrolyte which remains in it until the electrochemical reaction is completed to the desired stage.

30 In most electrochemical processes of the type to which this cell is adapted, there is evolved a mixture of gases often in explosive proportions. In the case of the electrochemical oxidation of sodium chloride to sodium perchlorate for example, varying amounts and proportions of hydrogen, oxygen, and chlorine gases are evolved, and it is necessary, in order to avoid explosions, to remove this gas or dilute it with another gas to a mixture which is no longer explosive. Provision is made in my cell for the introduction of a sweeping out gas through the influent pipe 23 and the removal of the mixture of gases from the effluent pipe 24.

35 In electrochemical reactions requiring the use of platinum anodes, it is important, because of the high unit cost of platinum to use as small a quantity of the metal as possible. My platinum electrodes 17 consist of a thin sheet 20 of platinum, about .005 inch thick, which is punched

with numerous holes in order to provide ready circulation of the electrolyte through and around all portions of the platinum surface. The thin sheet of platinum is inserted through the cover plate 18 through an opening 19 provided therein. Above the cover plate, the upper end of the thin platinum sheet is pressed between relatively heavy sheets of copper 25, and the sandwich thus formed is bolted together between the vertical portions of L shaped bars 26 by bolts 29, which in turn are bolted along the horizontal sides to the cover plates 18 by means of threaded studs 27 of headed machine screws set in holes in the artificial stone cover plates 18. In order to prevent twisting and buckling of the extremely thin electrode sheet within the cell, it is positioned in substantially aligned position between depending glass bars 28 which are suspended from and rigidly held adjacent the platinum sheets 20 in countersunk holes 30 in the cover plates 18, the glass bars being provided with flanges 31 to fit in countersunk holes, being cemented in place by suitable chemically resistant material. The glass bars 28 are disposed at intervals along the length of the electrode and extend as far as the depth of the platinum sheet.

The cathode of the cell consists of the surfaces of the steel tank and the steel tubes used for water-cooling which are in contact with the electrolyte. An upright bar member welded to the flange on one side at the top edge of the tank provides a convenient electrical connection for the cathode to the bus bars of the electrical system.

My improved electrolytic cell is particularly adapted for electrochemical oxidation reactions which may utilize the high over-voltage of a platinum surface on the anode. My anode structure permitting the use of the very thin platinum material allows the commercial use of this metal for anodes whereas heavier self-aligning sheets of platinum are prohibitive in price, and platinum clad composite sheets with base metals such as copper have been found to disintegrate rapidly because of undetected pinholes in the thin platinum covering sheets. By using anodes of platinum metal only, even though extremely thin, the pin holes (sometimes potential or undetectable prior to actual anode use) which are characteristic of thin platinum sheets, do not cause any trouble because of the absence of the base metal contact in the electrolyte zone. In my anode structure, all contact of the platinum with other metals is outside and protected from electrochemical action.

By using the platinum anode, I am able to employ higher current densities per unit area, and higher voltages, which result in greater efficiency, and also in more heating of the electrolyte, and more danger of local overheating from non-uniform conductivity or for other causes. In order to maintain uniform and optimum conditions of operation of the cells, it is necessary to provide large capacity cooling means, which includes the pipe coils between the electrodes, and the outside cooling jackets. Uniformity of temperature and concentration within the electrolyte is also provided by the means for circulating the electrolyte in and out of the cell, and over the electrode surfaces to remove the generated gas thereon.

These characteristics of my improved electrochemical cell are advantageously employed in the process of electrochemically oxidizing sodium chlorate to sodium perchlorate, which is fully de-

scribed in my copending patent application Serial No. 625,857.

I claim:

1. An electrolytic cell comprising an elongated steel tank adapted to contain an aqueous electrolyte and to serve as cathode; and electrically insulating cover for said tank having openings for non-rigid platinum sheet anodes, vertically disposed anode-holding insulating rods rigidly supported by said cover along the perimeters of said openings and adapted to laterally position said sheet anodes to keep them in alignment; an anode member for said cell including rows of anode assemblies disposed lengthwise of said cell, each assembly consisting of a thin non-rigid sheet of platinum sandwiched between co-extensive sheets of another metal in the portion above said cover plate with metallic clamping bar members for said sandwich having attaching means to hold said assembly on the cover above the anode opening therein; means for maintaining temperature uniformity in the electrolyte including steel pipe coils for cooling medium disposed between the rows of platinum sheets and serving as cathode surfaces; and means for circulating the electrolyte in the cell around the anodes and from one end of the cell to the other including baffles, inlet pipes and overflow discharge openings.

2. An electrolytic cell comprising an elongated steel tank adapted to contain an aqueous electrolyte and to serve as cathode; jackets for circulation of cooling liquid on the walls of said tank; an electrically insulating cover for said tank having openings for non-rigid platinum sheet anodes; vertically disposed anode-holding insulating rods rigidly supported by said cover along the perimeters of said openings and adapted to laterally position said sheet anodes to keep them in alignment; an anode member for said cell including rows of anode assemblies disposed lengthwise of said cell, each assembly consisting of a thin non-rigid sheet of platinum sandwiched between co-extensive sheets of another metal in the portion above said cover plate with metallic clamping bar members for said sandwich having attaching means to hold said assembly on the cover above the anode opening therein; means for maintaining temperature uniformity in the electrolyte including steel pipe coils for cooling medium disposed between the rows of platinum sheets and interconnected to said jackets on said tank for common flow of cooling medium; said coils serving also as cathode surfaces; and means for circulating the electrolyte in the cell around the anodes and from one end of the cell to the other including baffles, inlet pipes and overflow discharge openings.

3. An electrolytic cell comprising an elongated steel tank adapted to contain an aqueous electrolyte and to serve as cathode; jackets for circulation of cooling liquid on the walls of said tank; an electrically insulating cover for said tank having openings for non-rigid platinum sheet anodes; vertically disposed anode-holding insulating rods rigidly supported by said cover along the perimeters of said openings and adapted to laterally position said sheet anodes to keep them in alignment; an anode member for said cell including rows of anode assemblies disposed lengthwise of said cell, each assembly consisting of a thin non-rigid sheet of platinum sandwiched between co-extensive sheets of another metal in the portion above said cover plate with metallic clamping bar members for said sandwich having

attaching means to hold said assembly on the cover above the anode opening therein; means for maintaining temperature uniformity in the electrolyte including steel pipe coils for cooling medium disposed between the rows of platinum sheets and interconnected to said jackets on said tank for common flow of cooling medium; said coils serving also as cathode surfaces; and means for circulating the electrolyte in the cell around the anodes and from one end of the cell to the other including baffles, inlet pipes and overflow discharge openings; and means for introducing inert cooling gas between the cell cover and the upper level of the contained electrolyte and for withdrawing the inert gas along with the generated gas mixture from said cell whereby to cool the non-immersed portions of said anodes within said cell.
